CONTROL SYSTEM

Maurice E. Reagan, Pittsburgh, and Willard A. Derr, Wilkinsburg, Pa., assignors to Westinghouse Electric Corporation, East Pittsburgh, Pa., a corporation of Pennsylvania

Application November 28, 1945, Serial No. 631,395

9 Claims. (Cl. 290—30)

1

Our invention relates, generally, to control systems and it has reference, in particular, to automatic control systems for starting internal combustion engines.

Generally stated, it is an object of our invention to provide an automatic starting system for an internal combustion engine which is simple and inexpensive to manufacture and which is easy to operate.

More specifically, it is an object of our invention to provide for cranking the engine of an auxiliary generator periodically at timed intervals until it starts, when a supply of electrical energy from a normal source fails.

Another object of our invention is to provide for predetermined "on" and "off" periods for a starting motor of an engine until the engine starts, or until a predetermined number of attempts have been made to start the engine.

It is also an object of our invention to provide for determining the number of attempts to start an internal combustion engine by means of a chain of counting relays.

Yet another object of our invention is to provide an automatic cranking system wherein a starting sequence is continued for a predetermined number of times if the engine fails to start, or if it fails to run for more than a predetermined time when it does start.

A further object of the invention is to provide for connecting the starting motor of an internal combustion engine to a source of electrical energy for a starting operation, and to disconnect it therefrom as soon as the load is removed from the motor, indicating that the engine has started.

Other objects will, in part, be obvious and will, in part, be explained hereinafter.

In accordance with one embodiment of our invention, switch means energized from a normal source of electrical energy may be used to normally connect a load circuit to the normal source. When the normal source fails the switch means returns to the deenergized position and connects the load circuit to an auxiliary generator. The starting motor of an internal combustion engine driving an auxiliary generator is thereupon connected to a source of electrical energy for a predetermined time, or until the engine starts. If the engine fails to start the motor is disconnected from the source for a predetermined time, and this sequence is repeated a predetermined number of times under the control of a chain of counting relays. Should the engine start during a starting period, a series relay in the starting motor circuit operates to stop the starting sequence.

2

The counting chain is reset by a time delay relay which operates only a predetermined time after voltage is applied to the load circuit from the auxiliary generator. Whenever voltage is restored to the normal source, the load circuit is reconnected thereto and the internal combustion engine is shut down.

For a more complete understanding of the nature and scope of our invention, reference may be made to the following detailed description, which may be studied in connection with the accompanying drawing, in which the single figure is a diagrammatic view of a control system embodying the invention in one of its forms.

Referring to the drawing, the reference numeral 10 may denote, generally, a control system for a power circuit wherein a load circuit including a load 11 may be normally connected by switch means 12 to a source 13 of electrical energy through the conductors 14. The switch means may be provided with an operating winding 15 which is energized from the normal source 13, so that upon failure of the normal source the switch means returns to the deenergized position and connects the load to an auxiliary generator 17 which is provided with an internal combustion driving engine 18 having a starting motor 20.

A starting switch 21 having an operating winding 22 may be provided for connecting the starting motor 20 to a source of electrical energy such as the battery 23 in response to operation of a starting control relay 25 which has an operating winding 26.

In order to provide for predetermined "on" and "off" periods of the starting motor 20, "on" timing means comprising, for example, pendulum type relays 27 and 28 may be provided in conjunction with timing relays 29 and 30, respectively, which are preferably of the slow release type. The relay 27 controls the operation of the relay 29 through the actuation of armature 32, which may be of the pendulum type and adapted to make intermittent contact for maintaining the relay 29 in the energized position for a predetermined interval of time after the pendulum type relay is deenergized. The pendulum relay 28 is controlled by the timing relay 29, and in turn controls the timing relay 30. The "off" time periods may be controlled by a pendulum type relay 35 having an armature 36 for maintaining a slow release relay 37 in the energized position for a predetermined time after deenergization of the relay 35.

For the purposes of providing a predetermined number of "on" and "off" periods in sequence,

counting means 40 may be provided comprising, for example, a plurality of counting relays 41 through 45 which may be connected so as to be sequentially operable in conjunction with a plurality of sequence relays 48, 49 and 50. A master relay 52 may be provided for controlling the operation of the counting and sequence relays under the control of the starting control relay 25 and a load responsive relay 54 which may be operable in response to a predetermined value of current through its operating winding 55 in the operating circuit of the starting motor 20.

A starting relay 56 may be provided for operating in response to deenergization of the load responsive relay 54 during a starting interval for affecting deenergization of the starting control relay 25. A voltage responsive relay 58 may be connected in the output circuit of the auxiliary generator 17 to provide a holding circuit for the starting relay 56 as soon as the voltage of the generator 17 reaches a predetermined value. A field relay 59 may be provided for affecting energization of the field winding 60 of the auxiliary generator as soon as the engine 18 reaches a predetermined speed. Means such as the throttle control device 62 may be provided for opening the throttle of the engine whenever the load is transferred to the generator 17, and for shutting down the engine 18 whenever the switch means 12 returns to the energized position in response to a predetermined voltage from the normal source of supply 13.

In order to provide for controlling the starting sequence so as to take care of momentary starts of the engine which do not last for a predetermined time, means such as the time delay release relay 64 may be provided. The relay 64 may be of any type well known in the art, and may, for example, comprise an operating winding 65 energized in response to energization of the load 11 and arranged for actuating an armature 66 which may be provided with a clutch lever 67 for actuating a movable clutch member 68 which is disposed to engage a clutch member 69. The clutch member 69 may be driven by means of a motor 70 for actuating cam members 72 and 73 against the pressure of a spring 74 for actuating latch members 75 and 76. These latch members interfere with the movable contact arms 77 and 78 of the relay, which in the released position engage stationary contact members 77a and 78a, respectively. When the operating winding 65 is deenergized, the clutch members 68 and 69 separate, so that the cams 72 and 73 are actuated by the spring 74 to release the latches 75 and 76 almost immediately, whereas by the contact arms 77 and 78 which are actuated by the spring 79 to make contact with the stationary contact members 77a and 78a are locked in the contact making position.

When voltage is reapplied to the load circuit 10 and the operating winding 65 is energized, the clutch members 68 and 69 are immediately re-engaged, but a substantial time delay of approximately three minutes occurs before the latch members 75 and 76 are actuated by the cams 72 and 73 in response to operation of the motor 70 to permit separation of the contact arms 77 and 78 from their stationary contact members 77a and 78a. Accordingly, even though the engine 17 should start momentarily, unless it runs for the full interval of three minutes, the counting system 40 will not be reset and the starting sequence will continue to the end of the sequence. Should the engine run for an interval of longer than three minutes, the time delay release relay 75

64 will reset the counting system 40 and a new starting sequence will be commenced.

Under normal operating conditions, the operating winding 15 is energized from the source 13, and the switch means 12 is in the operated position as shown, thus connecting the load 11 to the source 13 through contact members 12a, 12b and 12c. Upon the failure of voltage of the source 13, or the reduction thereof below a predetermined value, the switch means 12 returns to the deenergized position, disconnecting the load 11 from the source 13, and connecting it to the auxiliary generator 17 through contact members 12a, 12b and 12c and their respective back contacts. The throttle control device 62 is energized through contact member 12d and its back contacts to prepare the engine 18 for starting.

As soon as voltage is removed from the load 11, the operating winding 65 of the time delay release relay 64 is deenergized, and the relay operates contact arms 77, 78 into engagement with stationary contact members 77a, 78a, respectively. An energizing circuit is thereupon prepared from the pendulum relay 27 from negative through the operating winding of the relay 27, through back contact and armature 52d of the master relay 52, conductor 80, contact members 77a, contact arm 77, and a cutout switch 81 to positive.

Relay 27 operates and provides an energizing circuit for the slow release relay 29 from negative through the operating winding of the relay 29, front contact and armature 32, conductors 82, 83 and 80, stationary contact members 77a, contact arm 77, and the cutout switch 81 to positive.

Operation of the relay 29 provides an obvious energizing circuit for the pendulum relay 28 through armature 29a and front contact of the slow release relay 29. The pendulum relay 28 thereupon provides an obvious energizing circuit for the slow release relay 30 through armature 33 and front contact.

Operation of the relay 30 provides an energizing circuit for the start control relay 25 extending from negative through operating winding 26, back contact and armature 46b of the counting relay 46, conductor 84, conductor 85, back contact and armature 31a of the slow release relay 37, conductor 86, armature 30a and front contact of the slow release relay 30, conductor 87, back contact and armature 56a of the start relay 56, conductors 89, 83 and 80, contact member 77a, contact arm 77 and cutout switch 81 to positive.

The start control relay 25 operates, closing armature 25a and front contacts to provide an energizing circuit for the operating winding 22 of the starting switch 21 which connects the starting motor 20 to the battery 23. Armature 25c and front contacts provide a holding circuit in shunt with armature 31a and its back contact.

As soon as the starting motor 20 is energized, the load responsive relay 54 operates and provides an energizing circuit for the master relay 52, extending from negative through the operating winding of the relay 52 through conductor 92, front contacts and armature 25b, front contacts and armature 54a of the load responsive relay, through conductors 89, 83 and 80, stationary contact 77a, contact arm 77 and cutout switch 81 to positive.

The master relay 52 operates, providing a holding circuit with the load responsive relay 54 through armature 52b and front contact, and at the same time deenergizing the operating wind-

ing of the pendulum relay 27 by separating armature 52d from its back contact.

The armature 32 of the pendulum relay 27 thereupon vibrates for a predetermined interval of time, during which the slow release relay 29 is periodically energized and deenergized so as to be maintained in the energized position. At the end of this time, the relay 29 releases armature 29a and interrupts the energizing circuit of the pendulum relay 28, which likewise retains the slow release relay 30 in the energized position for a predetermined time interval.

When the master relay operates, armature 52c engages its front contact to provide an energizing circuit for the first counting relay 41, extending from negative to the operating winding of the relay 41 through conductor 95, back contact and armature 48a, back contact and armature 49a, back contacts and armature 50a, and front contacts and armature 52c to positive. The counting relay 41 operates and prepares an energizing circuit for the sequence relay 48 through armature 46a, and front contact. Operation of the sequence relay 48 is prevented by reason of a shunt maintained by the master relay through front contact and armature 52c.

At the end of the time interval determined by the relays 27, 28, 29 and 30, the start control relay 25 is deenergized by the opening of armature 30a from its front contact. Accordingly, the starting switch 21 returns to the deenergized position, and the load responsive relay 54 is deenergized. The master relay 52 is deenergized by the opening of armature 25b from its front contacts, and the shunt is thereupon removed from the sequence relay 48 so that it operates. At the same time, the "off" timing period is initiated by the opening of armature 52e and front contacts of the master relay, which deenergizes the pendulum relay 35, and the "on" timing relays 27, 28, 29 and 30 are again energized.

At the end of a predetermined interval of time the slow release relay 37 releases and prepares the start control relay 25 for reenergization since the slow release relay 30 is already energized. Accordingly, the start control relay 25 completes an energizing circuit for the starting switch 21, and the starting motor 20 is again energized in an attempt to start the engine 18. As soon as the motor 20 is connected to the battery 23, the load responsive relay 54 picks up, and an energizing circuit is again prepared for the master relay 52. Operation of this relay again starts the "on" timing period by sequentially affecting deenergization of the relays 27, 29, 28 and 30. At the same time the "off" timing relays 35 and 37 are energized to prepare for a subsequent "off" timing interval.

When the master relay 52 operates for the second time, the second counting relay 42 is energized through a circuit extending from negative through front contact and armature 41b, of the first counting relay, front contacts and armature 48a of the sequence relay 48, back contacts and armature 49a of the sequence relay 49, back contact and armature 50b of the sequence relay 50, and front contacts and armature 52c of the master relay.

When the master relay is subsequently deenergized upon the return of the slow release relay 37 to the deenergized position, the sequence relay 49 is energized in series circuit relation with the counting relay 45 upon the removal of the shunt through front contact and armature 52c of the master relay. If this sequence continues, the

counting relay 41 and the sequence relay 48 are deenergized upon operation of the sequence relay 49 by the opening of armature 49b and its back contact. The counting relays 43, 44, 45 and 46 are sequentially operated in conjunction with the sequence relays 50, 48, 49 and 50, respectively, upon subsequent operations of the master relay. If the engine 18 is started during any of the six starting attempts counted by the relays 41 through 46, the system is locked out.

Should the engine 18 start during any one of the starting sequences, voltage will be applied to the field winding of the generator 17 by the field relay 59 whenever the engine 18 attains a predetermined operating speed. Accordingly, the voltage relay 58 will operate in response to the voltage of the generator.

Since the load responsive relay 54 returns to the deenergized position when the load is removed from the starting motor 20 by the engine 18 starting, an energizing circuit is prepared for the start relay 56, extending from negative through the operating winding of the start relay through conductor 96, conductor 97, front contact and armature 52a of the master relay 52 and back contact and contact member 54a of the load responsive relay 54, through conductors 89, 83 and 80, contact 77a, contact arm 77, and cut-out switch 81 to positive.

The start relay 56 operates, and interrupts the energizing circuit for the start control relay 25 by opening armature 56a from its back contact. A holding circuit is provided for the start relay 56 through armature 56a and its front contact. The starting switch 21 is thereby deenergized, disconnecting the starting motor 20 from the battery.

As soon as the voltage is applied to the load 11 from the generator 17, the operating winding 65 of the time delay release relay 64 is energized, and the motor 70 begins to operate to actuate the latch members 75 and 76. Due to the gear reduction between the motor 70 and the cams 72 and 73, a relatively long interval of time on the order of three minutes is required for this operation. Accordingly, the counting means 40 will not be reset until the end of such time interval.

Should the motor 18 start, but continue to run for less than three minutes, the counting chain 50 will not be reset and the starting sequence will be continued from wherever it left off, proceeding to the end of the sequence of six operations, in case the engine does not start. However, should the engine 18 start and run for more than three minutes, the time delay release relay 64 will have operated to open contact arm 77 and contact member 77a. The counting means 40 are thereby deenergized, and should the engine 18 thereafter stop, a completely new sequence of starting operations will be initiated.

Should the voltage of the source 13 return to normal, the switch 12 operates to disconnect the load 11 from the auxiliary generator 17 and connect it to the source 13. At the same time, the throttle control device 62 is deenergized by the opening of armature 12d from its back contacts so that the engine 18 is shut down.

From the above description and the accompanying drawing, it will be apparent that we have provided an automatic starting system which is both simple and effective. A plurality of ten-second attempts to start the emergency engine driven generator are provided in the event of loss of the normal source of power with a five-second "off" interval between each period of cranking.

Lockout of the equipment is affected after six unsuccessful attempts to start the engine. Accordingly, the maximum protection is provided for both the starting equipment and the continuity of service is maintained at a relatively high standard.

Since certain changes may be made in the above-described construction, and different embodiments of the invention may be made without departing from the spirit or scope thereof, it is intended that all the matter contained in the above description and shown in the accompanying drawing shall be considered as illustrative, and not in a limiting sense.

We claim as our invention:

1. In a control system for an internal combustion engine having a starting motor, switch means operable to connect the motor to a source of electrical energy, timing means operable to effect operation of the switch means for a predetermined time, additional timing means operable to render the switch means inoperative for a predetermined time, control means operable to provide for operation of the switch means a predetermined number of times, and means responsive to the armature current of the engine starting motor operable to prevent further operation of the switch means.
2. For use in starting an internal combustion engine having a starting motor, a first timing means, switch means operable under the control of said first timing means to connect the motor to a source of electrical energy for a predetermined time, a second timing means operable to prevent operation of the switch means for a predetermined time, control means responsive to the connection of the motor to said source, and counting means comprising a chain of relays sequentially operable in response to operation of the control means to provide for a predetermined maximum number of operations of the switch means in sequence.
3. For use in a control system for an internal combustion engine having a starting motor and arranged to drive an emergency generator for supplying electrical energy to a load circuit a control system comprising, control means operable in response to a predetermined electrical condition of the load circuit, timing means operable to effect connection of the starting motor to a source of electrical energy for a predetermined time, additional timing means operable to prevent reconnection of the motor to the source for a predetermined time, relay means operable in response to connection of the motor to the source to effect alternate operation of the timing means, and a chain of sequentially operable relays operable under the control of the relay means to limit the number of alternate operations of the timing means.
4. A control system for the starting motor of an internal combustion engine comprising, timing means operable to effect connection of the motor to a source of electrical energy for a predetermined time, additional timing means preventing connection of the motor to the source during a predetermined time, control means responsive to energization of the starting motor, counting means including a chain of counting relays sequentially responsive to energization of the starting motor operable to limit the number of connections of the motor to the source, and means responsive to a predetermined reduction in the load on the starting motor for preventing further connections of the starting motor to the source.

5. For uses in controlling the starting motor of an internal combustion engine connected to drive an auxiliary generator disposed to be connected by switch means to a load circuit in response to predetermined conditions of energization of the load circuit, a control system comprising, means responsive to predetermined conditions of energization of the load circuit to connect the auxiliary generator to the load circuit to improve said conditions, timing means operable in response to said means, switch means operable to connect the starting motor to a source of electrical energy for a predetermined time in response to operation of the timing means, additional timing means operable to prevent operation of the switch means for a predetermined time, counting means operable to limit the number of operations of the switch means in a sequence, control means responsive to energization of the starting motor controlling the operations of the timing means and counting means, means responsive to a reduction of the load on the starting motor during a starting cycle operable to prevent further reclosures of the switch means, and circuit means controlled by the means responsive to said predetermined condition of energization operable to render the control system ineffective when the load condition is improved.

6. In a power system, an auxiliary generator driven by an internal combustion engine having an electric starting motor, switch means operable to connect a load circuit to a normal source of electrical energy in response to predetermined conditions of energization from said normal source and operable upon a reduction in said condition to disconnect the load circuit from said normal source and connect it to the auxiliary generator, time delay means operable immediately in response to the reduction in said condition, timing means operable in response to operation of the time delay means to effect connection of the starting motor to a source of electrical energy for a predetermined time, additional timing means operable to prevent connection of the starting motor to the source for a predetermined time, a master control relay operable in response to connection of the motor to the source for controlling the timing means, control means responsive to starting of the engine for effecting disconnection of the starting motor from the source, and means responsive to the terminal voltage of the generator to maintain the starting motor disconnected, said time delay means being operable a predetermined time after energization of the load circuit to reset the timing and counting means for providing a new cycle for subsequent starting of the motor.

7. In a control system, an auxiliary generator driven by an internal combustion engine having a starting motor, switch means normally operable to connect a load circuit to a normal source of electrical energy in response to a predetermined voltage of said normal source, said switch means being operable when the voltage of the normal source falls below a predetermined value to connect the load circuit to the auxiliary generator, switch means operable to connect the starting motor to a source of electrical energy for a predetermined time, control means responsive to a predetermined value of current supplied to the starting motor, timing means operable after a predetermined time to render the switch means inoperative, additional timing means operable to maintain the switch means inopera-

tive for a predetermined time, counting means operable to provide a maximum number of operations of the switch means in a sequence, a master relay responsive to operation of the control means for effecting alternate operations of said timing means and additional timing means and initiating operation of the counting means, means responsive to a return of the control means to the inoperative position during operation of the timing means for rendering the switch means inoperative, and means responsive to operation of the switch means upon restoration of the predetermined voltage condition to the normal source to reset the counting means.

8. In combination, an auxiliary generator connected to an internal combustion engine having a starting motor, switch means operable in response to energization of a normal source to connect a load circuit to said source, said switch means being operable upon deenergization of said source to connect the load circuit to the auxiliary generator, control means operable to connect the starting motor to a source of electrical energy for a predetermined number of times at predetermined intervals, means responsive to starting of the engine during connection of the motor for effecting disconnection of the motor from the source, and time delay means operable after the engine runs for a predetermined time to reset the control means.

15

5 9. In a control system for a starting motor of an internal combustion engine, switch means operable to connect the motor to a source of electrical energy, timing means operable to provide timed operations of the switch means, counting means responsive to operations of the switch means to limit the number of timed operations of the switch means, and means responsive to a predetermined reduction in the current drawn by the motor during a timed operation of the switch means operable to interrupt said timed operations.
